BOTTLE COOLER

Lester U. Larkin, Atlanta, Ga., assignor to Larkin
Refrigerating Corporation, Atlanta, Ga., a cor-
poration of Georgia

Continuation of application Serial No. 689,312,
September 13, 1933. This application March
17, 1934, Serial No. 716,193

14 Claims. (Cl. 62—126)

This application is filed as a continuation of my pending application, Ser. No. 689,312 for Bottle cooler, filed September 13, 1933 and allowed January 18, 1934.

5 This invention relates to bottle cooling apparatus in general; and more particularly to apparatus for cooling bottles having substantially cylindrical bodies.

10 The main object of the invention is to provide a bottle cooling apparatus of the mechanical refrigeration type designed to cool any desired number of bottles and their liquid contents and to maintain them automatically at any desired temperature.

15 Other objects of the invention will become apparent as the detailed description thereof proceeds.

In the drawing:

20 Figure 1 is a central vertical section through a cooling cabinet embodying the present invention;

25 Figure 2 is a perspective view of a bottle cooling unit forming an essential part of the present invention and shown as detached from the cabinet illustrated in Figure 1;

Figure 3 is a perspective view, somewhat enlarged, of the cooling coil assembly forming part of the unit illustrated in Figures 1 and 2;

30 Figure 4 is a horizontal section taken on the line 4—4 of Figure 1; and

Figure 5 is an end elevation of the bottle holder shown in Figure 4.

35 In the drawing the invention is shown as installed in a cabinet 1 having the usual top, bottom, back and side walls, properly heat insulated in any suitable manner. The cabinet forms a cooling chamber 2 to which access may be had through a door 3 suitably hinged to permit such access.

40 Within the chamber 2 there is installed a bottle cooling unit designated generally by the reference character 4. The unit 4 in the present instance comprises a series of vacuum plates 5, 6, 7, 8 and 9, in which are arranged the coils 10, 11, 12, 45 13 and 14, respectively, the latter being shown joined at 18'. The plates 5 to 9, inclusive, each comprise separated walls of conducting material enclosing the respective coils 10 to 14, inclusive, in the manner disclosed in United States Patent No. 1,824,158, September 22, 1931. As disclosed in said patent, the compartments formed by the separated walls of the aforesaid plates are evacuated so as to cause the opposed walls to collapse against the opposite faces of the respective

coils to form intimate heat conducting contact with the coils.

The opposite sides of the plates 5, 6, 7, 8 and 9 are cooled by the flow of any suitable liquid refrigerant through the coils contained in the 60 plate compartments. As shown in Fig. 3, the several coils 10 to 14 are arranged in series so that the refrigerant entering the top plate 5, through the refrigerant connection 15, flows through all of the coils and emerges from the bottom of the unit through the exit connection 16. It is to be understood, of course, that the connections 15 and 16 are connected to a compressor of any suitable type for condensing and effecting proper circulation of refrigerant fluid, under the usual 65 thermostatic control, through the coils enclosed in the several plates.

As shown in Figure 2 of the drawing the lower face of the plate 5 has suitably secured thereto a series of substantially cylindrical bottle receiving receptacles 17. Each receptacle is suitably connected in intimate heat conducting relation to the lower face of the plate 5. Each of these receptacles is preferably made of tinmed brass and shaped to form spring sleeves of a size adapted to permit the reception of standard sized bottles having substantially cylindrical bodies. Each bottle receptacle 17 is suitably welded or otherwise secured in heat conducting relation to the lower face of the plate 5 along a line substantially 75 parallel to the axis of the receptacle. Diametrically opposite to its line of connection to the plate 5 each receptacle is split so as to yield to compensate for slight variations in the diameters of the bottles adapted to be inserted therein for 80 cooling purposes.

The outer end 18 of each receptacle 17 is preferably flared or made somewhat bell-shaped to facilitate insertion of a bottle therein. A strap 19, extending along the rearward edge of the plates 5 to 9, inclusive, and suitably secured to said edges serve as a stop to limit the insertion of the bottle in the receptacle 17 and to brace the series of vacuum plates properly spaced apart from each other in the unit.

100 The upper face of the plate 6 is provided with a series of bottle receptacles 17 secured thereto in the same manner as the receptacles are secured to the lower face of the plate 5. The row of receptacles secured to the plate 6 is separated 105 slightly from the row secured to the plate 5; and each receptacle contacts for heat conducting purposes with the plate to which it is connected, but is out of contact with the adjacent bottle receptacles. Rows of receptacles of the type just de- 110

scribed are similarly secured in the spaces between the plates 6 and 7, 7 and 8, and 8 and 9.

The arrangement of plates and bottle receiving receptacles may be varied as found convenient. It is not essential that the rows be arranged to face each other as shown in the drawing, nor that they should be limited to any particular number of rows. It is obvious that any desired number of bottle receptacles might be arranged 10 on the upper face of the plate 5 and on the lower face of the plate 9 providing the size of the cabinet will permit such arrangement, and it is found desirable to use such construction.

The unit is intended to be controlled thermally statically so as to cool the bottles arranged therein to any desired temperature. For the purpose of connecting the capillary bulb of a thermostatic switch to the unit each of the coils is provided with a small sleeve 25 adapted to serve as a contactor for the capillary bulb of a thermostatic control. The compartments formed by the several plates are supported by staggered braces 20, 21, 22 and 23.

It is thought that the invention and numerous 25 of its attendant advantages will be understood from the foregoing description, and it is obvious that numerous changes may be made in the form, construction and arrangement of the several parts without departing from the spirit or scope 30 of my invention, or sacrificing any of its attendant advantages; the form herein described being a preferred embodiment for the purpose of illustrating my invention.

What I claim is:

- 35 1. A bottle cooler comprising a plate, means for cooling said plate, and a substantially cylindrical heat conducting bottle receptacle fixed in heat conducting contact with a face of said plate and having its axis substantially parallel to said face.
- 40 2. A bottle cooler comprising a plate, means for cooling said plate, and a substantially cylindrical heat conducting bottle receptacle fixed in heat conducting contact with a face of said plate and having its axis substantially parallel to said face, said receptacle being of springy material and split lengthwise to yield radially and compensate for variations in the diameters of bottles inserted therein.
- 45 3. A bottle cooler comprising: a casing, cooling plates arranged substantially parallel to each other in said casing, means for cooling said plates, and heat conducting tubular receptacles secured in heat conducting contact with each of said plates.
- 50 4. A bottle cooler including a cooling plate formed by separated walls of heat conducting material, a cooling coil located in the space between said walls, means for circulating a cooling fluid through said coil, and tubular heat conducting receptacles secured in heat conducting relation to one of said walls.
- 55 5. A bottle cooler including a cooling plate formed by separated walls of heat conducting material, a cooling coil located in the space between said walls, means for circulating a cooling fluid

through said coil, and tubular heat conducting receptacles secured in heat conducting relation to one of said walls, said cooling receptacles being radially expansible to compensate for variations in the diameters of bottles inserted therein.

80

6. A bottle cooler including a cooling plate formed by separated walls of heat conducting material, from which the air is evacuated, a cooling coil located in the space between said walls, means for circulating a cooling fluid through said coil, tubular heat conducting receptacles secured in heat conducting relation to one of said walls.

85

7. A bottle cooling unit comprising: a series of heat conducting plates, means for cooling said plates, and substantially cylindrical heat conducting bottle receptacles secured in heat conducting contact with said plates.

90

8. A bottle cooling unit comprising: a series of heat conducting plates, means for cooling said plates, and substantially cylindrical heat conducting bottle receptacles secured in heat conducting contact with said plates, each receptacle being of springy material bell-shaped at one end and split lengthwise to compensate for variations in the diameters of bottles inserted therein.

95

9. A bottle cooler including a support adapted to have a cooling medium passed therethrough and a substantially cylindrical heat conducting bottle receptacle mounted on said support and in heat conducting contact therewith.

100

10. A bottle cooler including a support adapted to have a cooling medium passed therethrough and a substantially cylindrical heat conducting bottle receptacle mounted on said support and in heat conducting contact therewith, said receptacle being of springy material slit lengthwise to compensate for variations in the diameter of bottles inserted therein.

105

11. A bottle cooler comprising a frame including a cooling coil, a substantially cylindrical heat conducting bottle receptacle, and means for securing said bottle receptacle in heat exchanging relation to said coil.

110

12. A bottle cooler comprising a cooling coil, substantially cylindrical heat conducting bottle receptacles arranged on opposite sides of said coil, and means connecting said receptacles to said coil to effect exchange of heat between said coil and receptacles.

115

13. A bottle cooler including a support adapted to have a cooling medium passed therethrough, substantially cylindrical heat conducting bottle receptacles arranged on opposite sides of said support, and means connecting said receptacles to said support to effect exchange of heat between said receptacles and support.

120

14. A bottle cooler including a substantially cylindrical heat conducting bottle receptacle formed of springy sheet material and having a bell-shaped mouth and split lengthwise to compensate for variations in the diameters of bottles inserted therein a heat conducting support for said receptacle and in heat exchanging contact therewith and means for cooling said support.
